United States Patent Office

Des. 195,763
Patented July 30, 1963

195,763

FILAGREE PANEL

William Levy, 833 Chestnut St., Franklin Square,
Long Island, N.Y.

Filed Sept. 12, 1962, Ser. No. 71,661

Term of patent 14 years

(Cl. D13—1)

FIG. 1.

FIG. 2.

FIG. 1 is a front view of a filagree panel showing my new design; and

FIG. 2 is an edge view thereof.

The sides not shown are substantially the same as the ones shown.

I claim:

The ornamental design for a filagree panel, substantially as shown and described.
